COMBUSTION-ENGINE.

1,083,265.

Specification of Letters Patent.

Patented Dec. 30, 1913.

Application filed January 14, 1913. Serial No. 741,927.

To all whom it may concern:

Be it known that I, AUGUST BAUMANN, a citizen of Switzerland, residing at Augsburg, in the Kingdom of Bavaria and German Empire, have invented certain new and useful Improvements in Combustion-Engines, of which the following is a specification.

This invention relates to an improvement 10 in combustion-engines and more particularly to the means for cooling the cylinders and covers of cylinders of combustion engines of every kind and construction.

The method and means for cooling the 15 walls of combustion-engines, generally, consist in providing a current of cool water continually flowing along the walls to be kept cool. By experience it has been found, however, that this mode of cooling hitherto 20 practised is not at all satisfactory, to prove which fact it need only be pointed out that, in spite of such cooling means having been employed, the cylinders and covers of cylinders in such engines frequently are liable 25 to leakage caused by small rents or cracks in the walls or covers of the cylinders. It has been observed that such rents or cracks particularly occur in such portions of the 30 cylinders which are the most subjected to the intense heat of the combustion of the gases, particularly in the vicinity of the exhaust-valves. The cause of the formation of such rents or fissures may with good reason be attributed to the retaining of heat in such portions of the walls and covers which are most 35 exposed to the heat of the gases in combustion, such portions becoming overheated when cooling is not, or not sufficiently, applied. The consequence of such over-heating will always appear in a deformation of the wall, such deformation causing rents, cracks or fissures or damage of similar kind. But such fact that cracks or fissures most 40 frequently occur in the vicinity of the valve-seats, cannot be exclusively attributed to the heat retained in the walls from the passing currents of combusting gases. It ought to be taken into consideration, besides, that a considerable amount of heat is being stored 45 in the valve-carrier and the walls of the cylinder and cover, which heat, adding itself to the passing heat of the gases, not only causes an additional overheating of sundry portions, but also occasions a difference in 50 the temperature of different portions and

so increases the liability of various portions to be deformed and thereby to cause leaking.

My present invention is intended to overcome these difficulties in the cooling of combustion engines and, in particular, it shall increase the cooling effect in establishing special passages or channels for the cooling fluid, such channels or passages being so arranged to positively cool the portions of the cylinders, walls and covers, which are most subjected to overheating. The said channels or passages are so arranged as to cause the cooling fluid not only to give its cooling effect particularly at or near the portions most exposed to heat, but also to increase its 60 rapidity of flow when passing said portions, thereby securing such cooling effect, which is well apt to remove or to materially reduce any danger of deformation and leakage in the engine which might interfere with its 65 normal operation.

To make my invention perfectly understood, the novel means of cooling the heated parts are illustrated in the accompanying drawings, the peculiar ducts for the cooling 70 fluid being shown applied to a valve-box of a combustion engine.

Figure 1 is a cross section of a valve-box constructed according to my invention, and Fig. 2 is a cross-section of a valve-box showing a modification of the ducts for the cooling 75 fluid formed within said valve-box.

In the said drawings, *a* designates either the exhaust-valve chamber or the suction-valve-chamber of a four-cycle combustion-engine, or the scavenger-valve-chamber of a two-cycle combustion engine. The valve-seat *b*, together with the valve-chamber *a*, are located within the wall *c* of the cylinder or of its cover. The valve-seat *b*, and the 80 said wall *c*, together inclose an annular hollow space *d*. The said annular space *d* is connected by one or more ducts *e* to the feed- and exhaust-ports of the cooling fluid and by other ducts *f* to the chamber *g* containing 85 the cooling fluid.

According to the construction illustrated in Fig. 1, the cooling fluid is fed from the supply through the duct *e* directly into the annular space *d* between the valve-seat *b* 90 and the surrounding wall *c*, before the said fluid enters the chamber *g*. Owing to the fact that the cooling fluid is, first, caused to traverse the annular space *d*, a strong 95 cooling effect is obtained not only on the 100 cooling fluid.

valve seat *b*, which is particularly exposed to the hottest gases, but also on the wall *c* near to and surrounding the said valve-seat *b*, and the heat retained by said valve-seat *b* and by the surrounding wall of the cylinder or cover of the cylinder is almost entirely absorbed by the cooling fluid in passing through the annular space *d*. A deformation of the parts at or near the said valve-seat, and the fissures which might be occasioned by such deformations, are positively prevented in the manner described.

The cooling fluid, having passed through the annular space *d*, may, preferably, be further employed by being discharged through a plurality of radially disposed ducts *f* into the chamber *g*. The advantage derived from this arrangement of the ducts is obtained by the fact that the cooling fluid issuing from the narrow ducts *f* is discharged with great rapidity and eddying in its flow, into the chamber *g*, thereby causing an extremely lively flow of the fluid along the heated wall of the cylinder.

Instead of providing narrow ducts *f* between the annular space *d* and the fluid-chamber *g*, a continuous slot may be formed to connect said space *d* with the chamber *g*. A continuous slot of this kind offers the advantage of uniformly cooling the entire portion of the wall *c* between the space *d* and chamber; and, besides, of fully separating the valve-seat *b*, from the cylinder *c*, thereby allowing both of them to expand and contract independently of each other under the influence of heat or cooling fluid, so that any strain occurring in one of the two parts will not be transmitted to the other part.

By providing the annular space *d* between the valve-chamber *a* and the surrounding wall, a further advantage is obtained which consists in that, by removing said valve-chamber *a*, all the ducts or channels, through which the cooling fluid is made to pass, are laid open and made easily accessible. The said ducts or channels, accordingly, may be easily controlled and cleaned, if required. This facility in controlling the ducts and channels regarding the cooling fluid is of utmost importance for obtaining a permanent good cooling effect, because the portions most exposed to heat of the walls of the cylinder and cover are also most liable to deposition of incrustation from the water, such incrustation being a strong obstacle to the cooling effect of the cooling fluid on the surface to be cooled.

The supply of cooling fluid, of course, can be varied as desired and it should be well understood, that my invention is not limited to the mode and means of supplying the cooling fluid as described and shown with reference to Fig. 1. For instance, the cooling fluid may, first, be introduced into the chamber *g*, to flow from there through the ducts *f*, or a slot, into the annular space *d*, and, finally, to escape through the ducts or channels *e* to the exhaust pipes connected thereto. Or the annular space *d* may be supplied with a cooling fluid through ducts or channels *e* from a main supply, and the cooling fluid be discharged from said annular space by similar ducts *e* leading to or connected to exhaust pipes, the chamber *g*, in this case, being without any connection with the annular space *d*, the ducts *f* being omitted. A variety of similar arrangements of the several ducts and chambers may be substituted to obtain essentially the same effect, as before described. The essential features to be maintained consist in providing between the valve-seat and the surrounding wall one or more hollow spaces through which the cooling fluid is caused to flow and which, preferably, should communicate with the chamber *g* containing the cooling fluid, thereby enabling the cooling fluid issuing from said hollow space or spaces *d* at a comparatively low temperature, to be further utilized for cooling the engine. By maintaining such general features, it will be of no particular import, in which manner the said hollow space or spaces *d* may be shaped and located with relation to the other parts. To imagine another modification of a hollow space of this kind, it might be practicable to obtain a hollow space *d*, by forming a recess of any suitable shape into the side of the cylinder only, or into the outside of the valve-seat *b* only, or partly into the side of the cylinder and partly into the side of the valve-seat. In any case it is not essential in which manner the cooling fluid is supplied to the said hollow space or spaces, and in which manner it is discharged therefrom.

By applying the new means of cooling, as before described, the known means of cooling the valve proper will not in the least suffer; on the contrary, the cooling effect of the usual means for cooling the valve will in some degree be increased by the tendency of the means before described to cool the parts which surround the said valve proper.

Fig. 2 illustrates a special construction of the ducts or channels, through which the cooling fluid is supplied to the annular space *d*. According to this modification, the cooling fluid is supplied to the said annular space *d* from the valve-chamber *a* through the hollow tubular branches *h*; the cold water enters into the valve-chamber *a* through the supply-channel *i*; the said chamber, thereby, is cooled in the usual manner, and the cooling water then rises through the hollow branch-pipes or stays *h* and passes into the annular space *d*.

As has been stated before, the effect to be obtained does not essentially depend on the

direction of the cooling fluid in being supplied to and discharged from the annular space d , but it has been found preferable, in general, to feed the supply of cooling fluid, 5 first, into the space d , thence through the ducts f into the chamber g , as before described.

Claims:

In a combustion engine, the combination 10 with a cylinder having a water jacket and being provided with a valve chamber seat, said valve chamber seat being provided with a groove, said cylinder being provided with outlet passages extending from said groove

to the water jacket, a valve chamber adapted to rest on said seat and close the groove whereby said groove may form a passage for cooling fluid about the valve chamber, said valve chamber being provided with a hollow body communicating with said groove 20 when the valve chamber is seated and having a fluid inlet passage.

In testimony whereof I have affixed my signature in presence of two witnesses.

AUGUST BAUMANN.
